(57) **CLAIM**

The ornamental design for a vanity light, as shown and described.

DESCRIPTION

FIG. 1 is a perspective view of a vanity light showing the claimed design;

FIG. 2 is another perspective view thereof;

FIG. 3 is a left side view thereof;

FIG. 4 is a right side view thereof;

FIG. 5 is a rear elevational view thereof;

FIG. 6 is a front elevational view thereof;

FIG. 7 is a top plan view thereof;

FIG. 8 is a bottom plan view thereof;

FIG. 9 is a perspective view of the vanity light shown in an alternate configuration of use; and,

FIG. 10 is a partial enlarged view of FIG. 9 thereof.

The broken lines depict portions of the vanity light that form no part of the claimed design. The additional dot-dash lines surrounding the detail views in FIGS. 9-10 are for annotative purposes only and form no part thereof.
